UNITED STATES PATENT OFFICE.

ARTHUR L. BREITENSTEIN, OF AKRON, OHIO, ASSIGNOR TO RUBBER PRODUCTS COMPANY, OF BARBERTON, OHIO, A CORPORATION OF OHIO.

DESIGN FOR AN ELASTIC VEHICLE-TIRE.

57,072.

Specification for Design.

Patented Feb. 8, 1921.

Application filed April 22, 1920. Serial No. 375,904. Term of patent 14 years.

To all whom it may concern:

Be it known that I, ARTHUR L. BREITENSTEIN, a citizen of the United States, residing at Akron, in the county of Summit and State of Ohio, have invented a new, original, and ornamental Design for Elastic Vehicle-Tires, of which the following is a specification, reference being had to the accompanying drawings, forming a part thereof.

Figure 1 is a plan view of a portion of an elastic vehicle tire, showing my new design, and

Fig. 2 is a side elevation of same.

I claim:

The ornamental design for an elastic vehicle tire as shown.

ARTHUR L. BREITENSTEIN.
